UNITED STATES PATENT OFFICE.

CARY S. COX, OF FRESNO, CALIFORNIA, ASSIGNOR OF ONE-HALF TO JESSE M. COX
AND ONE-HALF TO FRANCES COX WHITT, BOTH OF FRESNO, CALIFORNIA.

COTTON GIN.

Application filed July 20, 1927. Serial No. 207,307.

This invention relates to a cotton gin.

An object of the invention is the provision of a gin for removing fibers from the seeds while at the same time separating the seeds from the fibers during the removal of the fibers.

Another object of the invention is the provision of a cotton gin for removing fibers from the cotton seeds while said seeds are located in a restricted space in close association with the teeth of the gin so that not only the fibers are readily removed by the teeth but the seeds are separately discharged free of cotton without interfering with the removal of the lint, an air blower being employed in conjunction with the gin for aiding in removing the fibers from the space in which the seeds are moving through a tortuous path.

This invention will be best understood from a consideration of the following detailed description, in view of the accompanying drawings forming a part of the specification; nevertheless it is to be understood that the invention is not confined to the disclosure, being susceptible of such changes and modifications which shall define no material departure from the salient features of the invention as expressed in the appended claims.

In the drawings,—

Figure 1 is a longitudinal side view of the cotton gin constructed in accordance with the principles of my invention;

Figure 2 is a plan view of the same;

Figure 3 is a longitudinal vertical section of the device;

Figure 4 is a transverse vertical section taken along the line 4—4 of Figure 3;

Figure 5 is a bottom plan view of a shell concave shape for directing the movements of the seeds;

Figure 6 is a fragmentary vertical section of a modified form;

Figure 7 is a section taken along the line 7—7 of Figure 6.

Referring particularly to the drawings 10 designates a pair of longitudinal beams which are braced transversely by means of bars 11 and supported by standards 12. These standards are mounted on beams 13 resting upon cross bars 14. The longitudinal beams 10 are provided with bearings 15 and 16 in which are respectively mounted shafts 17 and 18.

Hopper 20 is located between the pair of spaced beams 10 and supported by means of metal bars 21 and 22 secured to the beams 10. A feeding device driven by shaft 26 is located within the transversely disposed 60 semi-circular housing 24, which is in communication with the hopper 20 and is connected in such a manner that no open spaces are provided to permit the accidental discharge of the cotton from the housing and hopper. The feeding device consists of a plurality of veins connected by the sleeve 23 rigid with the shaft 26 and are rotated in the direction indicated by the arrow in Figure 3 so that the material indicated at 70 27 is forced upwardly and into engagement with the teeth 28 whence it is carried into the concave member generally designated by the numeral 29 which will be presently described.

Referring more particularly to Figure 4 it will be seen that teeth are arranged at the periphery of a plurality of disks 30 which are spaced from each other by disks 31 which have a smooth periphery and which are of 80 less diameter than the disks 30 which are provided with teeth so that angular spaces are provided between the peripheries of alternate disks.

A semi-circular housing 32 is hinged at 85 33 on the longitudinal beams 10 and braces the ginning device in spaced relation with the teeth 28 so that a semi-circular space is provided in which the concave member 29 is located. Said housing is removably connected at 34 with the longitudinal beams 10 so that the housing may be elevated when desired for inspecting the teeth or the mechanism located within the housing. The housing 32 has side walls 35 which have 90 semi-circular flanges 36 riveted at 37 to the housing whereby the ginning device is thoroughly enclosed at the upper end. The arcuate shaped plate 38 embraces the bottom of the ginning device in close association 95 with the teeth 28, one end of the curved member 38 being secured at 39 to the housing 24. The other end is secured as shown at 40 to a discharge chute 51 which is secured by means of an angle arm 52 to the beams 10. This chute is adapted to receive the seeds which are discharged from the ginning device.

The concave member 29 is best illustrated in Figure 5. The concave member has a 110

pair of ears 53 standing rearwardly which are rolled at 54 to receive the shaft 33. The forward ends of the concave member are provided with ears 55 adapted to receive the bolt 34 for securing the forward end of the concave to the longitudinal beams 10. On the inner face of the concave member 29 are provided a plurality of ribs 56 and 57. The ribs are curved to conform to the curvature 5 of the member 29 and may be formed integrally therewith or secured in any approved manner. These ribs extend at an angle to a vertical plane passing transversely through the concave member and terminate short of the end of the concave member. At the forward end are provided a plurality of ribs 58 arranged at an angle to the ribs 56 and 57 and inclined to those ribs in an opposite direction. Another series of 10 ribs 59 are disposed adjacent the rear end of the concave member and on the inner face and are directed outwardly away from the rear end of the ribs 56 and 57 and at substantially a right angle to said ribs. These 15 ribs are shorter than the ribs 57 and are curved to conform to the curvature of the concave member 29. It will be seen by this particular construction of rib formation that a plurality of tortuous paths 60, 61 and 62 are provided through which the seeds must 20 travel before being discharged into the chute 51 while the lint is being removed from the said seeds.

A plurality of seed separators 63 are secured to the various ribs in spaced relation and are countersunk into the face of the ribs so that the outer face of the bars 63 are in the same plane with the outer face of the ribs. The bars 63 aid in maintaining the 30 seeds in the spaces between the ribs and for guiding the seeds towards the discharge end of the concave member 29.

The ribs are provided with passages extending therethrough and through the concave metal member 29 through which the lint may be drawn either by suction or by air pressure, as will be presently explained, and into the space 65 between the housing 32 and the concave member 29.

The housing 32 has a discharge opening 70 for lint through which the lint is drawn by suction and through a pipe 71 into a housing 72 in which is mounted for rotation a fan 73 having blades 74 radially disposed for creating suction. Said fan is driven by means of the shaft 18 and the lint is discharged through a conduit 75 in open communication with the housing 72. The discharge opening 70 for the housing 32 is 50 embraced by a conduit 76 either formed integrally with the said housing or connected thereto and is in direct communication at 77 with the conduit 71.

The shaft 26 is driven in an opposite direction to the shaft 17 through a twisted

belt 80 trained over a drum 81 on the shaft 26 and a drum 82 on the shaft 17. Shaft 18 is driven through a chain 83 from the shaft 17 and a sprocket 84. Shaft 17 is driven by means of a drum 85 rigid with the said shaft 76 and a belt 86 connected with any suitable source of power.

The operation of my device is as follows: The fan of feeding device 25 is driven in the direction indicated by the arrow in Figure 3, which is opposite to the direction of rotation of the disks 30. The cotton 27 is fed through the teeth 28 whereby the seeds and lint are carried up through the ribs in concave member 29 and the lint is removed as the various teeth come in contact with the lint and force the same therethrough. The suction created by the fan 73 draws the lint through the passages 64 in the ribs into the space 65, then through the conduit 76 and conduit 71 whence it is discharged through the conduit 75 for further treatment.

As the lint is being removed from the seeds said seeds travel through the tortuous paths 60, 61 and 62 between the ribs so that the teeth of the various disks 30 will aid in removing the lint from the seeds while the seeds are being moved over the top of the disks and discharged into the member 51.

The separator bars 63 at the inner end of the concave member 29 aid in guiding the seeds into the discharge member by permitting the lint to be drawn through the passages in the ribs by the suction fan 73.

In the modified form shown in Figures 6 and 7, the disks 90 and 91 have different diameters and each is provided with a series of teeth at the periphery shown at 92 and 93 respectively. The ribs 94 extend sufficiently downwardly and are provided with slots 95 and 96 to respectively receive the disks 90 and 91, thereby restricting the space but providing a sufficient space at 95 and 96 to permit the seeds to be drawn therethrough during the removal of the lint. These ribs, as has been previously described, extend inwardly from a concave member 97, with the ribs being located in staggered relation in order to provide for a tortuous path 100 whereby the teeth of different disks will engage the lint on the seeds, thus aiding in removal of the same.

I claim:

1. A cotton gin having a rotor provided with a plurality of teeth, a housing embracing the rotor and provided with a plurality of ribs on an inner face thereof and closely associated with the teeth, said ribs being in staggered relation to provide tracks for the cotton seeds, an air suction chamber associated with the housing, said ribs having a plurality of openings connecting the space between the housing and the teeth with the air chamber.

2. A cotton gin comprising a rotor provided with a plurality of teeth, a housing curved to conform to the curvature of the rotor and spaced from the teeth, a plurality of ribs carried by the inner face of the housing and in close association with the teeth, said ribs providing channels for the movement of cotton seeds, a casing embracing the housing and forming with said housing an air suction chamber, said ribs having passages therethrough connecting the space between the housing and the teeth with the air chamber. 75
3. A cotton gin comprising a rotor provided with a plurality of teeth, a housing curved to conform to the curvature of the rotor and spaced from the teeth, a plurality of ribs carried by the inner face of the housing and in close association with the teeth, said ribs providing channels for the movement of cotton seeds, a casing embracing the housing and forming with said housing an air suction chamber, said ribs having passages therethrough connecting the space between the housing and the teeth with the air chamber, said ribs being arranged in rows with the ribs in each row being in staggered relation with the ribs in an adjacent row. 80
4. A cotton gin comprising a rotor provided with a plurality of teeth, a housing curved to conform to the curvature of the rotor and spaced from the teeth, a plurality of ribs carried by the inner face of the housing and in close association with the teeth, said ribs providing channels for the movement of cotton seeds, a casing embracing the housing and forming with said housing an air suction chamber, said ribs having passages therethrough connecting the space between the housing and the teeth with the air chamber, said ribs being arranged in a plurality of rows, the centrally disposed row of ribs being located at an angle to the ribs in adjacent rows. 85
5. A cotton gin comprising a rotor provided with a plurality of teeth, a housing curved to conform to the curvature of the rotor and spaced from the teeth, a plurality of ribs carried by the inner face of the housing and in close association with the teeth, said ribs providing channels for the movement of cotton seeds, a casing embracing the housing and forming with said housing an air suction chamber, said ribs having passages therethrough connecting the space between the housing and the teeth with the air chamber, the ribs being arranged in rows with the ribs in each row being curved and displaced laterally and at an angle to a plane passing transversely and at right angles to the axis of the rotor. 90
6. A cotton gin having a rotor provided with a plurality of teeth, a housing embracing the rotor and provided with a plurality of ribs on an inner face thereof and closely associated with the teeth, said ribs being in staggered relation to provide tracks for the cotton seeds, an air suction chamber associated with the housing, said ribs having a plurality of openings connecting the space between the housing and the teeth with the air chamber, means for feeding cotton to the teeth, and means for discharging the seeds from the housing. 95
7. A cotton gin having a rotor provided with a plurality of teeth, a housing embracing the rotor and provided with a plurality of ribs on an inner face thereof and closely associated with the teeth, said ribs being in staggered relation to provide tracks for the cotton seeds, an air suction chamber associated with the housing, said ribs having a plurality of openings connecting the space between the housing and the teeth with the air chamber, means for feeding cotton to the teeth and separating bars secured to the ribs for aiding in directing the seeds from the housing. 100
8. A cotton gin comprising a rotor provided with a plurality of teeth, a housing curved to conform to the curvature of the rotor and spaced from the teeth, a plurality of ribs carried by the inner face of the housing and in close association with the teeth, said ribs providing channels for the movement of cotton seeds, a casing embracing the housing and forming with said housing an air suction chamber, said ribs having passages therethrough connecting the space between the housing and the teeth with the air chamber, means for feeding cotton to the teeth and separating bars secured to the ribs with the outer faces of the bars in the same plane with the outer surface of the ribs. 105
9. A cotton gin comprising a rotor provided with a plurality of teeth, a housing curved to conform to the curvature of the rotor and spaced from the teeth, a plurality of ribs carried by the inner face of the housing and in close association with the teeth, said ribs providing channels for the movement of cotton seeds, a casing embracing the housing and forming with said housing an air suction chamber, said ribs having passages therethrough connecting the space between the housing and the teeth with the air chamber, means for feeding cotton to the teeth, and separating bars secured to the ribs with the outer faces of the bars in the same plane with the outer surface of the ribs, and means for forcing air through the air chamber for drawing the lint through the openings in the housing into the air chamber and for causing the lint to be discharged from the air chamber. 110
10. A cotton gin having a rotor provided with a plurality of teeth, a housing embracing the rotor and provided with a plurality of ribs on an inner face thereof and closely 115
11. A cotton gin having a rotor provided with a plurality of teeth, a housing embracing the rotor and provided with a plurality of ribs on an inner face thereof and closely 120
12. A cotton gin having a rotor provided with a plurality of teeth, a housing embracing the rotor and provided with a plurality of ribs on an inner face thereof and closely 125

- associated with the teeth, said ribs being in staggered relation to provide tracks for the cotton seeds, an air suction chamber associated with the housing, said ribs having a plurality of openings connecting the space between the housing and the teeth with the air chamber, said rotor consisting of a plurality of disks in spaced relation and carrying teeth.
- 10 11. A cotton gin having a rotor provided with a plurality of teeth, a housing embracing the rotor and provided with a plurality of ribs on an inner face thereof and closely

associated with the teeth, said ribs being in staggered relation to provide tracks for the cotton seeds, an air suction chamber associated with the housing, said ribs having a plurality of openings connecting the space between the housing and the teeth with the air chamber, said rotor consisting of a plurality of disks in spaced relation and carrying teeth, and disks alternately disposed relative to the first mentioned disks and having a different diameter from the first mentioned disks.

CARY S. COX.
